CLAIM

The ornamental design for a flexible curling dustpan, as shown and described.

DESCRIPTION

FIG. 1 is a top perspective view of the flexible curling dustpan;

FIG. 2 is a front edge view thereof;

FIG. 3 is a top elevational view thereof;

FIG. 4 is a rear edge view thereof;

FIG. 5 is a bottom plan view thereof;

FIG. 6 is a perspective view thereof in a fully curled condition in an enlarged scale, the broken line showing of the broom being for illustrative purposes only and forms no part of the claimed design; and,

FIG. 7 is a perspective view thereof in a partially curled condition.
